Attorney

UNITED STATES PATENT OFFICE

DAVID H. DOUGLAS, OF CROPSEYVILLE, NEW YORK

MAGAZINE PENCIL

Application filed June 23, 1928. Serial No. 287,729.

My present invention pertains to magazine pencils, and contemplates the provision of a magazine pencil characterized by the capacity to carry a number of leads, and by mechanism for effectively feeding each lead rectilinearly incident to the use thereof and for positioning a fresh lead for rectilinear movement thereof when the same becomes necessary during the continuous general use of the pencil.

Other objects and practical advantages of the invention will be fully understood from the following description and claims when the same are read in connection with the drawings, accompanying and forming a part of this specification, in which:

Figure 1 is a view of the pencil partly in elevation and partly in diametrical section constituting the best practical embodiment 20 of my invention of which I am cognizant, the sectional portion being on the line 1—1 of Figure 2.

Figure 2 is a transverse section of the pencil, on the line 2—2 of Figure 1.

Figure 3 is an elevation of the internal body per se of the pencil, in which is contained its working elements and which is intended to fit snugly inside the case as shown.

Figure 4 is a top view of Figure 3 with parts omitted.

Figure 5 is a lower end view of Figure 3.

Figure 6 is a top view of the upper detachable part of the pencil in which is contained the device for controlling the manual operation of the pencil.

Similar numerals of reference designate corresponding parts in all of the views of the drawings. Among other elements, my 40 novel pencil comprises a cylindrical casing body 1, preferably of metal and detachably connected at its lower end, preferably through the medium of a screw thread, with a taper member 10 in which is a longitudinal bore 3. At its ends remote from the taper end 2 the casing body 1 is provided with a circumferential fastening member 4, the said member 4 being grooved and being provided with an upwardly flared portion 5. 50 The fastener member 4 is possessed of re-

siliency, in order that the cap 6 may be sprung on and off the casing body 1 and this without liability of the cap 6 being casually displaced during the ordinary use of the pencil.

Interiorly, the cap 6 is provided with a rib 7, Figure 1, annular in form, and having an acting surface of convex form in vertical section. The said rib 7 constitutes a fastener member, and incident to the placing of the cap on the casing body 1 is adapted to spring past the portion 5 and seat in the fastening member 4, so that the cap is detachably though securely fastened to the casing body 1 in such a manner as not to interfere with the turning of the cap about its axis. The cap 6 is also provided interiorly with a portion 8, movable with the cap and having a disc like lower end 9 provided at 10, with an annular gear, (Figures 1 and 6).

The said gear is adapted when rotated, to serve as a driving means, as hereinafter described.

Arranged as illustrated within the casing body 1 is the internal body 18, which contains the working parts of the pencil and to which is attached a pin sprocket wheel 12, as shown, also an idler wheel 16. Trained around these wheels is a perforated belt made of any suitable material, said belt being designated by 13, and being equipped with equi-distant lugs 14, on which are driving and guiding balls 15. These balls are arranged to operate a cylinder 17, Figures 1 and 2, which in turn, is connected to the internal body 18 by screws 19 and 20 and plates 19^x and 20^x in such a manner that the screws will constitute journals for the said cylinder 17. The plate 19^x which forms part of the internal body 18 has a slot 22 in its upper portion and also has a portion which extends downwardly from said upper portion and then horizontally to the opposite side of the casing body 1. At 21 is a filling cover above said lower horizontal portion of the plate 19^x, so arranged that it will protect and retain the leads contained in the cylinder 17, and it will be noted that on a slight turn of the said cover 21, the openings therein shown will become co-inci-

dent with the lead chambers in the cylinder 17, thereby allowing the filling of all of the lead chambers with the exception of four which are not exposed by the cover 21, and which are necessarily empty for the proper operation of the pencil.

The cover 21 is not necessary for the operation of a pencil but is simply to shield the parts and to help make the pencil fool proof. The openings in the cover 21 are off center from the openings in the cylinder 17 and the necessarily corresponding openings in the plate 19^x, and by a slight clockwise movement of cover 21 said cover manifestly 15 will be brought into a coincident position with the corresponding openings in the cylinder and plates which are always at the same position with respect to one another excepting during that part of the operation 20 when the ball 15 is turning the cylinder 17 through its movement from one lead to another ~~in~~ one. At this point it would never be necessary to use the cover 21 as it would be sometime after this movement 25 before it would be discovered that the pencil required refilling. However it is entirely proper and possible that any empty lead chambers may be filled at any time through the proper openings and therefore makes 30 it possible to have all tubes filled but the one up which the rising ball 15 is traveling.

The arms 14 are not intended to pass through the slot 22 but pass under the plate in which the slot is formed. There is sufficient room for said arms to run clear of the internal body 18 as will be seen from the drawing. The slot 22 is simply for the pins 11 to pass through so that said pins may be engaged with the openings 10 in the cap 40 of the pencil so that turning of the cap will transmit the necessary movement by means of the meshed teeth 10 and 11 to the operating parts of the pencil.

The parts are so relatively arranged that 45 the distance between adjoining lead chambers of the cylinder 13 is not greater than approximately one-half the diameter of the driving ball 15 and the position of the idler wheel 16 with respect to the pencil bore 3 is such that the opening of the pencil bore 3 in the upper face of the lower part or taper 2 is at a distance below the center line of wheel 16, equal to one-half of the diameter of the ball 15.

50 The operation of the pencil is as follows: By rotating the cap 6, the gear 9, engaging the pins 11 on the socket wheel 12, the upper part of which protrudes through the opening 22, will cause the wheel 12 to turn and move the belt 13, to which is attached the arms 14 which carry the balls 15. The balls 15 will enter and move downwardly in one of the lead chambers which is in coincidence with the bore 3, pushing the lead ahead of it and out through the said bore 3 to writing posi-

tion. When the ball has reached a position so that its center is on the center line of the pulley 16 it will have entirely displaced the lead from the lead chamber and will then start to turn through an arc, of adequate radius, and with it will turn the cylinder 17 to such position that the other ball 15 will enter another loaded chamber and the operation will be repeated until all of the leads in the cylinder are used in succession.

To permit of the turning of the cylinder 17 and the protruding of the ball 15 from the lead chamber, a runway 23 is provided in the taper portion 2, Figure 1. The said runway also acts as a means whereby the upper portion of the pencil bore 3 may be cleared so as to form a guide for the new incoming lead. As the ball 15 never leaves a lead chamber from the time it enters said chamber on its downward stroke until it arrives at a point of equal elevation, it serves as a locking device to hold the cylinder 17 in rigid position at all times, while the lead is being moved rectilinearly from a lead chamber of the cylinder and also while the other ball is leaving the cylinder on its upward stroke and is about to enter a loaded chamber of the cylinder. The chambers of the cylinder 17 are designated 17^x.

It will be noted that my improvement provides for a lead completely leaving its respective lead chamber prior to the time when one of the balls 15 starts to revolve the cylinder 17 about its axis to the required position.

It will be readily gathered from the foregoing that notwithstanding the capacity of my novel pencil and the great length of lead that may be used, the pencil is simple and inexpensive in construction, is adapted to be used with facility and is generally capable of withstanding the usage to which magazine pencils are ordinarily subjected.

I have entered into a detailed description of the construction and operative arrangement of the parts embraced in the present and preferred embodiment of my invention, in order to impart a full, clear and exact understanding of the said embodiment. I do not desire, however, to be understood as confining myself to the construction and arrangement of parts as disclosed, my invention being defined by my appended claims within the scope of which structural changes and changes in arrangement may be made without departure from my invention.

I claim:

1. In a pencil, a magazine, including a plurality of chambers movable about a center, and propelling means arranged alongside of said magazine, and including a belt, and followers on said belt, and lower and upper gears about which the belt is passed, each follower at the completion of the 125

traverse of one stretch of the belt being adapted to turn the magazine for the presentation of a fresh lead to the pencil discharge, and also being arranged at the completion of the traverse of the other stretch of the belt followed by a movement about the other gear to enter a fresh chamber of the magazine.

2. A pencil having a plurality of magazine chambers for holding leads movable about a center, and endless propelling means for moving leads in said chambers and for turning the magazine.

3. A pencil having a plurality of magazine chambers for holding leads movable about a center, and endless propelling means for moving leads in said chambers and for turning the magazine, in combination with means for moving said propelling means, and means forming a part of the pencil for actuating the last named means.

4. A pencil having a plurality of magazine chambers for holding leads movable about a center, an endless propelling means for moving leads in said chambers and for turning the magazine, in combination with means for moving the propelling means, a casing body, and a cap turnable relative to the casing body arranged to transmit motion to the means for moving the propelling means.

5. In a pencil, a magazine comprising a plurality of chambers movable about a center, and propelling means arranged alongside said magazine and including a belt and followers on said belt and lower and upper wheels about which the belt is passed, each follower at the completion of the traverse of one stretch of the belt being adapted to pass the magazine for the presentation of the fresh lead to the pencil discharge, and being also arranged at the completion of the traverse of the other stretch of the belt followed by a movement about the other wheel to enter another chamber of the magazine, in combination with a casing body, a taper member connected to said body and having a bore for the passage of leads, and a cap turnably and detachably connected with the casing body and equipped with means for cooperating with one of said wheels for moving the belt by turning of the cap.

6. A pencil having a taper member with a longitudinal central bore, a casing body connected to said member and having a fastener member at its end remote from the taper member, a rotary cap having a fastener member detachably engaged with the first named fastener member, a magazine comprising a plurality of lead holding chambers movable about its center, said chambers being open at their opposite ends, a belt mounted on wheels in the casing body and arranged along side of the magazine,

followers carried by the said belt and adapted to move leads rectilinearly in the magazine and to turn the magazine about its center, and means fixed with respect to the adjacent wheel and engaging with the cap whereby turning of the cap will be attended by movement of the followers.

7. A pencil having a taper member with a longitudinal central bore, a casing body connected to said taper member and having a fastener member at its end remote from the taper member, a rotary cap detachably engaged with said fastener member, a magazine comprising a plurality of lead holding chambers movable about the center, said chambers open at their opposite ends, a belt mounted on wheels in the casing body and arranged alongside of the magazine, followers carried by said belts and adapted to move leads rectilinearly in the magazine and to turn the magazine about its center, means fixed with respect to the adjacent wheel and engaging the cap whereby turning of the cap will be attended by movement of the followers, and apertured turnable means adapted to rest in opposed relation to the ends of the lead holding chambers of the magazine.

8. A magazine lead pencil comprising enclosing means provided with a lead discharge opening, a magazine arranged in said enclosing means and having a plurality of lead receiving chambers adapted to be made coincident with the lead discharge opening in succession, a turnable member carried by the enclosing means, and propelling means operable by said turnable means for feeding leads lengthwise of the magazine and discharge opening, and for turning the magazine for positioning another chamber in coincidence with the discharge opening.

In testimony whereof I affix my signature.
